present invention is to provide a plow of the sweep type which is provided with means whereby the pitch angle of the sweep and the longitudinal axis of the sweep can be varied and changed for replacement with a sweep of a different size to compensate for various plowing conditions.

UNITED STATES PATENT OFFICE

2,350,049

PLOW OF THE SWEEP TYPE

George W. Lee, Willow Springs, N. C.

Application November 13, 1941, Serial No. 418,969.

2 Claims.

(Cl. 97—118)

Generically, the present invention relates to plows of the sweep type, and specifically it has reference to a plow wherein it is possible to vary the pitch angle of the sweep and to change the longitudinal axis of the sweep relative to the body of the plow.

The majority of plows of this particular type, with the exception of Patent No. 2,226,665 issued December 31, 1940, to George W. Lee, have not been provided with any means whereby it is possible to obtain the double adjustment of the sweep above referred to. By virtue of the present construction, such double adjustment can be effected, and it is possible to replace quickly the sweep for one of another size to compensate for the various plowing conditions that may be encountered.

An object of the present invention is to provide a plow of the sweep type wherein the sweep may be easily and conveniently adjusted with relation to the share.

A further object is to provide a plow of the sweep type that is provided with means whereby the pitch angle of the sweep may be changed and the longitudinal axis of the sweep in regard to the body of the plow can be varied.

Yet a further object of this invention is to provide a plow of the sweep type which will permit the sweep to be easily and conveniently changed for replacement with a sweep of a different size to compensate for various plowing conditions.

To achieve the above and other advantageous objects, the invention broadly comprises a plow having a body portion comprising a plow fixed thereto. A support is pivotally attached to the body and a sweep is removably secured to the support. Means are provided to coact with the sweep and support whereby the position of the sweep with respect to the support and the position of the support in regard to the body can be altered.

In the drawings in which like numerals designate the same or similar parts:

Figure 1 is a view in perspective of a plow of the sweep type equipped with my invention.

Figure 2 is a bottom plan view of the plow shown in Figure 1.

Figure 3 is a vertical longitudinal sectional view of the plow shown in Figure 1.

Figure 4 is a sectional view taken along the line 4—4 of Figure 3 looking in the direction of the arrows.

Figure 5 is a front plan view of the adjusting casting.

Referring to Figure 1, the plow is shown in perspective view. The body 1 is formed at its rear end with an arcuate shaped stock 2. The stock 2 is attached to the inner face of a body portion 3 by upper and lower bolts 4 and 5 respectively, as perhaps best illustrated in Figure 3.

Figure 6 is a view of the casting shown in Figure 5 looking from the landside. Figure 7 is a top plan view of the casting shown in Figures 5 and 6.

Referring to Figure 1 it will be seen that a beam 1 is formed at its rear end with an arcuate shaped stock 2. The stock 2 is attached to the inner face of a body portion 3 by upper and lower bolts 4 and 5 respectively, as perhaps best illustrated in Figure 3.

Referring now to Figure 2 it can be seen that the forward end of the body 3 is provided with a frog 6 that carries an inwardly bent portion 7 which is parallel with the body 3. A share 8 is fixedly attached to the frog 6 by means of a bolt or the like 9.

A landside 10 is secured to the outer face of the body 3 by front and rear bolts 11 and 12 respectively. The front bolt 11 (see Figure 2) extends through the body 3 adjacent to the frog 6 and the outer end thereof projects through an aperture 13 formed in portion 7 of the frog 6, the purpose of which will later be more fully explained.

As hereinabove referred to one of the primary purposes of the present invention is to provide a structure whereby it is possible to vary the pitch angle of the sweep and to change the longitudinal axis of the sweep with respect to the body 3. To accomplish this, it will be noted that I have provided a casting designated generally 14. The casting is formed with a vertical member 15 provided on one edge with a right angular web 15' and carrying at its lower end a sleeve 16.

The sleeve 16 is disposed between the inner face of the body portion 3 and the member 7 of the frog and is pivotally secured to the body portion by virtue of the bolt 11 which extends therethrough. The lower end of a hand lever 17 is attached to the web 15' by bolts 18. A housing 19 is provided adjacent to the upper end of the lever and a spring pressed rack pawl 20 having at its lower end a tooth 21 is carried thereby. The tooth 21 is adapted to coact with spaced teeth 22 formed on an arcuate bar 23. The upper end of the bar is attached to the beam 1 as shown at 24 and the lower end thereof is secured to the stock 2 by the bolt 4.

Hand piece 25 is pivoted to the upper end of the lever 17 as shown at 26 and is connected to the upper end of pawl 20 by means of a link 27. Obviously, movement of the hand piece 25 toward the lever 17 will move the tooth 21 out of the spacings between the teeth 22 on the bar 23, thus permitting adjustment of the casting 14.

50 55

Angularly disposed with respect to the member 15 is an arcuate plate like element 28. The member 28 is formed with an arcuate slot 29 and an aperture 30. A sweep designated 31 is attached to the arcuate member 28 by a bolt 32 which extends through the aperture 30. A second bolt 33 projects through the arcuate slot 29 and it is thought apparent that by varying the location of the bolt in the slot it is possible to effect various adjustments of the sweep relative to a casting 14. It will be noted that the member 28 is at an angle to the horizontal plane passing through the axis of the sleeve 16 and that it is also at an angle to the vertical plane passing through the same axis. By virtue of this angular relationship the sweep 31 can be moved through the arc of a cone.

A fork 35 is suitably secured to the rear extremity of the body 3 and the lower ends of the plow handles 36 are affixed to the arms of the fork. Braces 37 are attached to the plow handles 36 and the beam 1 for added strength and rigidity to the plow.

It will be appreciated that sweep 31 can be adjusted relative to the arcuate member 28 and that the position of the member 14 in regard to the body 3 can also be varied. More specifically, by manipulation of the bolt 33 in the slot 29 the position of the sweep 31 with respect to the member 28 can be altered and by operation of the lever 17 the location of the casting 14 in regard to the body portion 3 may be changed.

This particular construction will enable the pitch angle of the sweep to be varied and it is also feasible to alter a change in the longitudinal axis of the sweep with respect to the body portion.

By being able to change the position of the casting 14 in regard to the body portion 3 through the manipulation of the lever 17 it is possible to permit a desired amount of soil to be rowed about plants during their cultivation.

approximately the same amount of earth from a furrow when the plow is used in the opposite direction.

The structure whereby I am able to obtain the double adjustment of the sweep is very simple and can be readily incorporated with the majority of plows that are now available on the open market. The unit is simple in construction and operation and can be manufactured at a reasonable cost.

While I have shown and described the preferred embodiment of my invention, I wish it to be understood that I do not confine myself to the precise details of construction herein set forth by way of illustration, as it is apparent that many changes and variations may be made therein, by those skilled in the art, without departing from the spirit of the invention, or exceeding the scope of the appended claims.

I claim:

- 25 1. A plow construction comprising a body portion, a frog provided at the front end of the body portion, a share attached to the frog, an offset provided on the frog, a plate pivotally attached between the body portion and the offset and having an angular portion extending rearwardly therefrom, an arcuate slot in the angular portion, a sweep secured in the slot whereby vertical adjustment of the sweep may be effected and a lever attached to the plate to raise and lower the free end of the sweep.

30 2. In a plow construction, a body portion, a frog provided at the front end of the body portion, a share secured to the frog, an offset carried by the frog, a support pivotally attached between the body portion and the offset and provided with an angular portion extending rearwardly therefrom, an arcuate slot formed in the angular portion, a sweep secured in the slot whereby vertical adjustment of the sweep may be effected, and means to move the support to raise and lower the free end of the sweep.
